(57) **CLAIM**

The ornamental design for a catch, as shown and described.

DESCRIPTION

FIG. 1 is a top, front, and left side perspective view of a catch according to my new design;

FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof;

FIG. 7 is bottom plan view thereof; and,

FIG. 8 is a bottom, rear, and right side perspective view thereof.

The dot-dash broken lines represent boundaries of the claimed design and form no part of the claimed design. The dash-dash broken lines depict portions of the catch that form no part of the claimed design.
